UNITED STATES PATENT OFFICE.

CHARLES W. SIMPSON, OF LA FERIA, TEXAS.

ANTIFRICTION-BEARING SUPPORT FOR DRAWERS.

Original application filed May 27, 1926, Serial No. 112,118. Divided and this application filed November 26, 1926. Serial No. 150,851.

This invention relates to improvements in means for efficiently supporting drawers and the like in anti-friction bearings, such as roller or ball bearings.

- 5 The primary object of this invention is the provision of improved anti-friction supporting and bearing means for efficiently and compactly supporting drawers for practically noiseless and efficient operation.
- 10 A further object of this invention is the provision of means for efficiently supporting library or cabinet drawers with an anti-friction construction, compactly arranged, and so provided that the external appearance 15 of the drawers will not disclose the anti-friction construction.

Other objects and advantages of this invention will be apparent during the course of the following detailed description.

- 20 In the accompanying drawing, forming a part of this specification, and wherein similar reference characters designate corresponding parts throughout the several views,

25 Figure 1 is a fragmentary front elevation of a kitchen cabinet type of drawer, in connection with which the novel anti-friction bearing is used.

- Figure 2 is a transverse sectional view taken through the drawer and anti-friction 30 construction, as illustrated in Figure 1, substantially on the line 2—2 of Figure 3.

Figure 3 is a fragmentary plan view, of the novel drawer illustrated in Figures 1 and 2, showing the same closed and the compact relation of the novel anti-friction 35 supporting means therefor.

- Figure 4 is an enlarged fragmentary sectional view of the supporting anti-friction construction for the drawers illustrated in 40 Figure 2.

Figure 5 is a perspective view of the drawer opening and supporting flange and antifriction means formed therewith for receiving the type of drawer illustrated in 45 Figure 1.

Figure 6 is a fragmentary perspective view showing the drawer construction and anti-friction means therefor adapted to co-

operate with the drawer anti-friction construction.

Fig. 7 is a view of the stop member.

In the drawing, wherein for the purpose of illustration is shown only a preferred embodiment of the improved anti-friction drawer construction, the letter A may generally designate a drawer slidably housed within a casing B upon anti-friction bearings C at each side thereof.

The casing B for the drawer may be of any approved nature, such as a cabinet or library table casing, and for the purpose of this the same may be considered as having approved side walls 10 and 11, between which a compartment 12 is provided, wherein in the drawer A is slidably mounted.

The drawer A may include side walls 13 and 14, connected by a bottom wall 15, and front and rear walls 16 and 17 respectively, and said drawer is adapted to slide in the compartment 12 between the side walls 10 and 11; the spacing of the drawer side walls 13 and 14 being such that they are slightly spaced with respect to the inner surfaces of the casing walls 10 and 11, and in which spaces the anti-friction constructions above 75 mentioned are operable.

To hide the anti-friction construction C which operates in the space, the front wall 16 of the drawer A is provided with lateral flanges 19 and 20, which close the spaces by 80 projecting beyond the plane of the side walls 13 and 14, as illustrated in Figure 3 of the drawing, so that when the drawer is closed no portion of the space of the compartment 12 is visible from forwardly of the casing.

The means C for supporting the drawer or drawers A in an anti-friction relation upon the side walls 10 and 11, comprises spaced upper and lower elongated tracks 25 and 26 respectively, at the inner sides of each of 90 the walls 10 and 11, secured thereto in any approved manner to provide a space 27 between the bottom and top surfaces thereof respectively, within which may be slidably received the track flange or bar 30, which 95 is rigidly attached to the outer surface of

the side wall 13 or 14, of the drawer, as the case may be. It is of course understood that each side wall 13 and 14 is provided with the track strip 30, and that it operates in a channel 27 secured to the adjacent side wall of the casing.

Inwardly of the top surface of the lower track 26, it is preferred to provide a V-shaped groove 32, and the angle of the slope of the sides of this groove may vary from 10 60° to 90°, and the same should not relatively slope in planes greater than 90°. Inwardly of the groove 32 of each track 26, a forward ball bearing 35 is disposed, which 15 is limited to a path of travel slightly less than one-half the length of the track 26, being forwardly restrained by means of a stop block 37, in the front end of the groove 32, and at its rear path of travel being 20 limited by a stop block 38. Also, in each groove 32 is a rear ball bearing 39, limited to a length of travel along the groove for about the same distance as the travel of the ball bearing 35; the said bearing 39 25 being limited at its front end of travel by means of the stop block 38 and at its rear end of travel by means of a stop block 40.

When the drawer A is slipped into place, 30 the bottom surfaces of the side flanges 30 engage upon the top projecting portions of the ball bearings 35 and 39, for supporting the drawer in an anti-friction relation upon the track 26.

35 The grooves 32 have overhanging retaining flanges 42 and 43, as illustrated in Figure 4 of the drawings, to retain the ball bearings in place against accidental lifting of the same from the grooves; these flanges 40 overhanging the maximum diameter of the ball bearings in order to retain them in place against displacement.

At the rear portion of each of the flanges or tracks 30, inwardly of the top surfaces 45 thereof, a groove 50 is provided, which extends from the rear end 51 of its respective flange or track 30 to half way between the ends of the track 30; the groove 50 in cross section being identical with the cross section 50 of the groove 32, and as illustrated in Figure 4, and being adapted to support front and rear ball bearings 53 and 54 respectively, which are limited in their path of travel by front, intermediate and rear abutments 55, 56 and 57 respectively, to limit the movement 65 of the ball bearings to substantially the same length of travel at the front and rear ends of the grooves of said flanges or tracks 30.

60 It is readily apparent that when the tracks or flanges 30 are slipped into the channel between the upper and lower tracks 25 and 26 of the casing B, the upper projecting portions of the ball bearings 53 and 54 will 65 engage the under surfaces of the top tracks

25, to support the drawer A in a sliding relation in the casing B, to counteract the tipping effect when the same is extended, and permit easy sliding thereof, without binding.

70

From the foregoing description of this invention it is apparent that a novel type of anti-friction ball bearing support for drawers has been provided, which is susceptible of universal adaptation to various types of 75 drawers, and which may be used in connection with wooden, composition, or metal cabinet or table constructions.

This application is a divisional application from my co-pending United States application, Serial No. 112,118, filed May 27, 1926.

80

Various changes in the shape, size, and arrangement of parts may be made to the form of invention herein shown and described, without departing from the spirit of the same or the scope of the claims.

85

I claim:

1. In an anti-friction drawer supporting construction the combination of a casing having side walls, a drawer adapted to slide between the side walls of the casing including side walls, spaced parallel tracks at the inner sides of each of the casing side walls defining a channel therebetween, a track attached to the outer side of each side wall of the drawer and slidable in the channel between the adjacent tracks of the side walls of the casing, and anti-friction means between the tracks of the casing side walls and the upper and lower surfaces of the tracks of the drawer side walls, said anti-friction construction comprising elongated grooves substantially the length of the lower tracks inwardly of the upper surfaces of the lower tracks of the side walls of the casing and having ball bearings therein, and the tracks of the side walls of the drawer inwardly of the top surfaces thereof for substantially one-half the length of said drawer tracks from the rear end to intermediate the ends thereof having grooves with ball bearings positioned therein.

90

100 2. In an anti-friction supporting drawer construction the combination of a casing having side walls, a drawer adapted to slide between the side walls of the casing including side walls also, spaced parallel tracks at the inner sides of each of the casing side walls defining a channel therebetween, the lowermost of said tracks having an upwardly facing V-shaped groove along the length thereof subdivided by a stop block to provide a forward groove portion and a rearward groove portion, ball bearings in the forward groove portions of said lower tracks, ball bearings in the rearward groove portions of said tracks, a track attached to the outer side of each side wall of the drawer and slidable in the channel between the ad- 115 120 125 130

5 jacent tracks of the side walls of the casing, said tracks of the side walls of the drawer in the upper surfaces thereof having substantially V-shaped grooves therealong at the rear portions thereof only, means subdividing each of said last mentioned grooves into a forward groove portion and a rear groove portion, and anti-friction bearings

in each of said groove portions, the tracks of the side walls of the drawer bearing such a relation to the uppermost track of the side walls of the casing that the ball bearings of the tracks of the side walls of the drawer will engage the under surfaces of said uppermost casing side wall tracks.

CHARLES W. SIMPSON.
